BRAIDED EYE FOR SLING

Vincent C. J. Peterson, Forty Fort, Pa., assignor to American Chain & Cable Company, Inc., Bridgeport, Conn., a corporation of New York

Application February 27, 1946, Serial No. 650,682

3 Claims. (Cl. 87—8)

1

This invention relates to slings, and more particularly to the method of forming eyes in the ends thereof.

Slings of wire rope or cables are often fabricated by braiding because of the flexibility of such construction. Formation of an eye in the end of a braided structure is difficult, and the formation of such an eye without introducing weakness into the sling requires considerable skill and judgment. Furthermore, it is desirable to form an eye which does not cause any stiffness in the body of the sling adjacent thereto, as such stiffness interferes with the use of the sling in a so-called "choker" hitch.

It is therefore an object of the present invention to provide an eye and method for making it which do not introduce weakness into the structure.

It is a further object of the present invention to provide a method of forming an eye in a braided structure which can be readily practiced.

It is a further object of the present invention to provide a braided eye for a braided sling which does not depend upon supplementary fastening means to carry the load.

It is a further object of this invention to provide a braided eye on a braided sling without necessity for splicing together any of the individual parts comprising the sling body.

Referring now to the drawings:

Fig. 1 is a view showing part of the braided body of a sling ready for formation of an eye thereon;

Fig. 1a is an enlarged view of a section of Fig. 1, showing the disposition of the parts making up the braid;

Fig. 2 is a view similar to Fig. 1, showing the first step in the formation of an eye;

Figs. 3, 4 and 5 show respectively the second, third, and fourth steps; and

Fig. 6 shows a completed eye.

As can be seen from the figures, the body of the sling is braided of a number of parts. For the purpose of illustration the braid shown is an eight part braid, in the form of a braid of four pairs of parts. In Fig. 1a, the individual parts have been numbered 1 to 8, to facilitate tracing of the course of the parts. The structure of the braid may be visualized as pair 1, 2 and pair 3, 4 formed into a rope of four parts, the lay of the rope being to the right. Pair 5, 6 is laid in a rope with pair 7, 8, the lay being left in hand. These two ropes are intertwined, thus producing the braid shown. It is to be understood that any

2

form of braid can be utilized, and the braid shown is merely for the purposes of illustration.

Referring now to Figs. 1 and 2 to 6, the method of forming the eye is set forth. After the formation of the body braid, the parts are separated into two groups containing an equal number of parts. The separated groups should be long enough to form the complete eye, and extend down the sides of the body braid for a little distance.

The next step is to form a braid for a little less than half of the length of each of the groups, as shown in Fig. 2. This braid is shown as being in every respect identical to the braid of the body, with the exception that it is made of four parts, rather than of four pairs of parts. The braid should have about the same pitch as the body braid, to give a uniform appearance to the braid upon completion. A part is shaded in Fig. 2 and succeeding figures, extending through each group of parts, and designated "A" for the part in the left hand group, "B" for the part in the right hand group.

After the separate braids have been made and tied temporarily with seizings 9, they are brought together and interlaced as shown in Fig. 3. In order that there be no discontinuity at the meeting point after the eye is completed, it is preferable to have corresponding parts adjacent each other. Thus, parts A and B are adjacent each other. It will be noted that both these parts spiral around in the braid in a right hand direction. Similarly, each part in the left hand braid is adjacent a part in the right hand braid which corresponds to it.

As a next step, one of the groups is interwoven with the other. In Fig. 4, the part B is interwoven into the braid of the left hand group in such a manner that it is associated with part A exactly as parts 3 and 4 (Fig. 1a). If all of the parts of the right hand group are similarly paired with parts of the left hand braid, a braid will be produced which is identical in appearance with the braid of the body.

The process is repeated on the right side of the eye, resulting in the structure shown in Fig. 5. It will be noted that the parts A and B are paired together entirely around the eye, the parts ending in opposite sides of the eye. The same is true for all other parts, each one being paired with a part which starts from the opposite side of the eye. The temporary seizings are removed as soon as is convenient in the process of interweaving, and, as can be seen from Fig. 5, there is no joint present at any point around the eye.

In order to complete the eye, the loose ends are secured to the body of the sling, which can be done with a fitting pressed or swaged over them, or, as shown, by a seizing 10. Additional seizing 11 may be applied over parts of the eye which receive the greatest wear in use of the sling, to prevent wearing and breaking of wires which would endanger the hands and clothing of the workman handling the sling. It is to be understood that the seizing is not intended to contribute any strength to the eye, or keep it from slipping. That service is performed by the method of braiding.

The description is, for the purpose of illustration, directed to a type of braid involving paired parts. Theoretically, paired parts, with each part of a pair starting from the opposite side of the eye from the corresponding part, should result in a braid which is of greatest efficiency, as slipping would result in adjacent parts moving past each other. Thus, the maximum frictional holding power is developed. However, it is not necessary that the braid be made in this fashion, as many types of braid develop sufficient friction between the parts to permit utilization in the manner described. Further, the shown form involves the same type of braid for both the body and the eye. Such is not necessary. For instance, the body may be made of flat braid, for flexibility, while the eye may be made of round braid, to fit the hook better.

Furthermore, although the simplicity of the above described braided eye has much to recommend it, it is possible to fabricate an eye by simply dividing the parts into two groups, and interweaving them to form the desired braid. Such an eye requires only that the parts be divided into two groups, and the braided eye can then be formed with the parts from one group passing around the parts of the other group in proper relation to form the braid. It is of course to be understood that the paths taken by the parts of one group should be so related to the paths taken by the parts of the other group that there is sufficient opportunity for frictional resistance between parts of opposite groups to hold the eye together and permit approximately equal stress in each part.

There are braids of an odd number of parts which are well adapted to use in a sling body, because of their shape or flexibility characteristics. The above method of forming an eye can be used, but it is to be understood that the eye

will have a lower strength, and accordingly will not support all the load which the sling body is capable of sustaining. However, such construction is often desirable, and the advantages thereof may outweigh the increase in weight.

It will therefore be seen that the above description is intended to be illustrative, and not limitative, and that many variations in both the structure and the method of manufacture may be practised without departure from the scope of this invention, which is best apprehended by reference to the appended claims.

I claim:

1. In a sling of an even number of parts, an eye formed of said parts, half of said parts extending from the body of the sling around the eye in one direction, the remaining parts extending from the body of the sling around the eye in the opposite direction, each of the parts being paired with a part extending around the eye in an opposite direction, the pairs so formed being braided to form a braid of pairs throughout at least a portion of the eye.

2. The method of forming an eye for a multi-part sling comprising separating the parts of the sling into two equal groups, braiding the parts of each group together for a portion of the length of the parts in the group leaving the extremities unbraided, and interbraiding the unbraided portion of each part of each group into the braided portion of the other group.

3. The method of forming an eye for a multi-part sling comprising separating the parts of the sling into two equal groups, braiding the parts of each group together for a portion of the length of the parts in the group leaving the extremities unbraided, and passing the unbraided portion of each part of each group through the braided portion of the other group adjacent a part thereof to form a braid of pairs.

VINCENT C. J. PETERSON.
